UNITED STATES PATENT OFFICE.

HERMON L. VAN VALKENBURG, OF NORWOOD, OHIO, ASSIGNOR TO THE BULLOCK ELECTRIC MANUFACTURING COMPANY, A CORPORATION OF OHIO.

OIL-SWITCH.

No. 922,825.

Specification of Letters Patent.

Patented May 25, 1909.

Application filed August 25, 1905. Serial No. 275,844.

To all whom it may concern:

Be it known that I, HERMON L. VAN VALKENBURG, citizen of the United States, residing at Norwood, in the county of Hamilton and State of Ohio, have invented certain new and useful Improvements in Oil-Switches, of which the following is a full, clear, and exact specification.

My invention relates to switches, and particularly to oil switches intended for high voltage service.

One of the objects of my invention is to provide a switch of the multiple break type which will be simple in construction, durable, effective, and easy to assemble and with all parts easily removable for the purpose of repairs.

A further object is to provide a simple mechanism for raising or lowering the oil tank at will and for holding the same in its raised position.

A still further object is to provide an oil switch of the four-break type in which all danger of short-circuits between the contacts is eliminated.

My invention consists in certain novel details of construction and combination of elements set forth in the following description and appended claims.

Reference is had to the accompanying drawings, in which—

Figure 1 is a section of my improved switch, along the line 1—1 of Fig. 2, looking in the direction of the arrows, some of the elements being shown in elevation; Fig. 2 is a section of my switch approximately along the line 2—2 of Fig. 1; Fig. 3 is a plan view of my switch, the operating mechanism being removed and showing also portions of two other similar switches; Fig. 4 is a front elevation of my switch and supporting wall, showing in elevation the tank moving mechanism; and Fig. 5 is a section on a reduced scale, along the line 5—5 of Fig. 3.

I have shown in the drawings a four-break single-pole switch, two or more of which are adapted to be mounted side by side preferably in a concrete or brick wall, as shown at 1, 2, and 3 in Fig. 3. I wish it understood however that most of the features of my invention are not confined in their application to a switch of the single-pole four-break type, nor is it material in what manner my switch is supported. I have in this instance shown a switch support consisting of a rear wall 4

of concrete or brick having forwardly extending walls 5 forming compartments in each of which one of my switches is adapted to be mounted. Forming the cover for each of the compartments and resting on the rear and side walls is a slab or plate of insulating material 6 preferably of soapstone which supports the switch contacts, as will be described later. The slab of insulating material is held in place by bolts or tie-rods 7 embedded in the concrete or brick walls. These bolts support at their lower ends, channel irons 8, between which is a filler of concrete or cement 9.

Extending through, and babbitted or cemented to the slab 6 are two porcelain bushings 10, 10, into which are held preferably by cement vertical positive and negative contact terminal rods 11 and 11'. These two contact rods are connected to the main line leads or conductors 12 and 12' by threaded sleeves 13, one of which is shown in Fig. 1. Two inverted porcelain cups, 14, 14 are also held in the insulating slab by cement or any other suitable means. These cups and bushings are spaced equal distances apart and are arranged in a circle about the axis of the switch. Supported preferably by cement in these two cups 14 are the vertical auxiliary contact rods 15 and 15'. Adjustably secured to each of the rods 11, 11' and 15, 15' are contact-finger holders 16, on which are mounted contact fingers 17. The contact fingers on rods 11 and 15 are in the same horizontal plane, while the fingers on rods 11' and 15' are in another, but lower plane. Supported on the lower ends of the rods 11, 11', 15 and 15' by nuts 18 is a second slab of insulating material 19. This slab holds the rods in a fixed, parallel position. Journalized in the upper face of this slab is a vertical rotatable shaft 20 carrying the insulating drum 21, preferably of wood. Supported on this drum in two horizontal planes and at right angles to each other are the bridging cross-arms 22 and 22'. The cross-arms are arranged in planes to engage the fingers on the rods 11, 11', 15 and 15', the upper cross-arm 22 being adapted to engage the fingers on rods 11 and 15 and the lower cross-arm 22' being adapted to engage the fingers on the rods 11' and 15'. The two rods 15 and 15' are connected at their extremities by the connecting strap 23, the latter being held between nuts 18, 24. Thus it is seen that I

have a single-pole, four-break switch. When the latter is closed the path of the current is as follows—from the main positive lead 12 to contact terminal rod 11, through the upper cross-arm 22 to contact rod 15 through strap 23 to contact rod 15', through cross-arm 22' to contact terminal rod 11' and to negative lead 12'. The contacts are so arranged that the circuits are closed or broken at the four points simultaneously and therefore the spark at break will be distributed at the four points and will be comparatively small even at high voltages. The shaft 20 passes through the plate 25, above the slab 6 and is connected at its outer extremity to the arm 26, to which may be connected any suitable operating mechanism. The collar 27 holds the shaft from vertical movement. When the switch is open there is considerable difference of potential between the contacts. In order to prevent an arc from jumping between the contacts in the two planes I separate the contacts by a novel form of insulating barrier or partition. This barrier consists of two or more sheets or plates of insulating material 28 spaced apart so that when assembled there will be a layer of oil between each adjacent pair of sheets. Each sheet or plate entirely surrounds the drum, being here shown as composed of four parts or quadrants supported on the rods 11, 11', 15 and 15'. By building up the insulating sheets or plates of sections in this manner they can be more readily assembled. The rods are in this instance shown as surrounded by sleeves of insulating material 29 and 30, and the sheets or plates 28 are held between washers 31 of insulating material and spaced apart by washers 32. The washers are mounted on the sleeves 29 between sections of the sleeves 30. I wish it understood, however, that it is immaterial how the barrier is supported, having merely shown one method which may be employed. The oil between the sheets is the principal insulator, the sheets of insulating material serving simply to prevent the spark from blowing away the oil and starting a short-circuit between the contacts. Any number of sheets may be employed, I having shown in this instance only two.

One of the important features of my invention is my oil tank lifting and holding mechanism, which will now be described.

The oil tank is shown at 33, and is normally held against the lower side of the slab 6 in such a manner as to surround all the switch contacts. The tank may be made of any suitable material and is lined on the inner side with insulating material, as is shown at 34. Located at each side and near the rear of the tank are two vertical guide rods 35. Pivoted at 36 on each of these rods 35 is a forwardly extending arm 37, which arms 37 are connected at their outer free ends by a

cross-rod 38. Pivoted to the arms 37 substantially midway between the ends thereof are two upwardly extending arms 39 which engage lugs 40 at the sides of the oil tank. The tank is provided at each side with two or more lugs or shoes 41 which engage the guide rods 35. The entire weight of the tank is taken by the arms 39, which are arranged at such an angle that there is always a back pressure holding the shoes against the guide rods. Thus by simply swinging the arms 37, the tank can be lowered from the normal upper position to the lower position, shown by dotted lines in Fig. 5. I have here shown two hooks 42 for engaging the cross-rod 38 to hold the tank in its upper position. These hooks are suspended on bolts 43 by wing-nuts 44. Thus when it is desired to hold the tank in the upper position, the rod is engaged by the hooks 42, and the nuts 44 are turned to raise the tank into close contact with the slab 6. Thus it is seen that my tank lifting mechanism is simple, effective, and can be quickly operated.

Having thus described my invention, what I claim as new—and desire to secure by Letters Patent, is:

1. In a four-break single-pole switch, a supporting plate, four insulated parallel rods extending therefrom, and arranged in a circle at equal distances apart, two of said rods being connected to the main line leads and the other two being connected together, contact fingers on each of said rods, the fingers on two diametrically opposite rods being in the same horizontal plane, the fingers on the other two rods being in another lower plane, and a rotatable insulating member having bridging contact arms arranged at angles of 90° with each other and in planes to engage the contact fingers.

2. In a multiple break switch, a horizontal supporting member, a pair of main contact rods extending through said supporting member and being adapted to be connected to line leads or conductors, a pair of secondary or auxiliary contact rods extending downward from said supporting member, all said contact rods being equally spaced about the axis of the switch, said main contact rods having contact members arranged in different horizontal planes, and each of said auxiliary contact rods having a contact member diametrically opposite and in the plane of the contact member on one of the main contact rods, means electrically connecting said auxiliary contact rods, and a centrally located rotary switch member having two contact members, each arranged to bridge the contact members on a main and an auxiliary contact rod.

3. In an oil switch, an oil tank, a centrally located vertical rotary switch member, positive and negative contact terminals extending downward into the tank and having sta-

- tionary contacts arranged in different horizontal planes, auxiliary stationary contacts arranged opposite and in the planes of the contacts connected to the positive and negative terminals, bridging contact members carried by the rotary switch member and arranged in planes to bridge the stationary contacts, and a horizontal insulating barrier between the contacts of the positive and negative terminals. 5
4. In a multibreak switch, a horizontal supporting member, a pair of insulating bushings extending through the same, contact rods secured in said bushings and being adapted to be connected to line leads or conductors, a pair of inverted cup shaped insulators secured in said horizontal supporting member, a pair of secondary or auxiliary contact rods having their upper ends extending into and secured to said insulators, all of said contact rods being equally spaced about the axis of the switch, said main contact rods having contact members arranged in different horizontal planes, 10 each of said auxiliary contact rods having a contact member diametrically opposite and in the plane of the contact members on one of said main contact rods, means electrically connecting said auxiliary contact rods, and a centrally located rotary switch member having two contact members arranged so as to bridge the contact members on the main and on the auxiliary contact rods. 15
5. In a switch, an oil tank, a plurality of contact rods in said tank, contacts on said rods, said contact rods being arranged at equal distances apart about the center of the tank, and insulating barriers or partitions between the contacts, each including a sheet or plate of insulating material composed of sector-like sections mounted on the contact rods. 20
6. In an oil switch, a plurality of stationary contacts, a central rotary switch member and a separating barrier comprising a plurality of spaced parallel sheets of insulating material, each entirely surrounding the rotary switch member, and formed of sector-like sections. 25
7. In an oil switch, an oil tank, a plurality of stationary contacts surrounded by oil, a central rotary contact carrying drum, and a barrier or partition separating the contacts, said barrier comprising a plurality of sheets of insulating material, spaced apart so that between adjacent sheets there will be a layer of oil, each entirely surrounding the rotary drum and formed of wedge-shaped sections. 30
8. In a single pole, four break switch, four equally spaced vertical contact rods, contacts carried thereby, said contacts being arranged in two planes, one vertically above the other, and a separating barrier comprising a plurality of sheets or plates of insulating material, each formed of sector-like quadrants supported on said contact rods. 35
9. In an oil switch, a horizontal supporting member, an oil tank, and means for raising and lowering said tank comprising a pair of levers connected to a stationary support and a pair of links pivoted to said levers and connected to opposite sides of the tank, and means for holding the levers and tank in raised position. 40
10. In an oil switch, a horizontal support for the switch mechanism, an oil tank, mechanism for swinging said tank toward and away from said support comprising a pair of pivoted levers connected together at their free ends and having operative connection intermediate their ends to opposite sides of the tank, and means for attaching the outer free end of said mechanism to said support to hold the tank in its normal upper position. 45
11. In an oil switch, a horizontal supporting member, an oil tank, a pair of vertical guides along which said tank is adapted to be moved and means for moving said tank along said guides comprising a pivoted lever connected to a stationary member and having operative connection with the tank, and means for attaching the outer end of the lever to the support so as to hold the tank in its upper position. 50
12. In an oil switch, a movable oil tank, means for moving said tank, comprising a lever pivoted to a stationary member, and a link connected to said lever and to said tank, and means for holding said lever and tank in raised position. 55
13. In an oil switch, a movable oil tank, means for lifting and lowering said tank at will comprising a lever arm, a link connecting said lever arm to said tank, and vertical guide rods between which said tank is adapted to move, and means for holding the tank and tank moving mechanism in raised position. 60
14. In an oil switch, a horizontal support, an oil tank, means for raising and lowering said tank comprising a pair of levers pivoted to a support and having operative connection to opposite sides of the tank, means connecting together the free ends of the levers, and means on the horizontal support in a position to engage the connecting means of the levers to hold the tank in its raised position. 65
